Charles D. Austin, Cincinnati, Ohio, assignor to
Advertising Displays, Inc., Covington, Ky., a
corporation of Kentucky

Application February 18, 1943, Serial No. 109,568

Term of patent 14 years

To all whom it may concern:

Be it known that I, Charles D. Austin, a citizen of the United States of America, residing at Cincinnati, in the county of Hamilton, State of Ohio, have invented a new, original, and ornamental Design for an Illuminable Magnifying Glass, of which the following is a specification, reference being had to the accompanying drawing, forming a part thereof.

Fig. 1 is a top view of an illuminable magnifying glass showing my new design.

Fig. 2 is a side view of the illuminable magnifying glass of Fig. 1.

Fig. 3 is a front end view of the illuminable magnifying glass of Fig. 1.

Fig. 4 is a rear end view of the illuminable magnifying glass of Fig. 1.

I claim:

The ornamental design for an illuminable magnifying glass, as shown.

CHARLES D. AUSTIN.
